United States Patent Office.

W. R. THOMAS, OF CATASSAUQUA, PENNSYLVANIA.

Letters Patent No. 73,407, dated January 14, 1868.

IMPROVED ANNEALING-FURNACE.

The Schedule referred to in these Letters Patent and making part of the same.

TO ALL WHOM IT MAY CONCERN:

Be it known that I, W. R. THOMAS, of Catassauqua, Lehigh county, Pennsylvania, have invented a new and useful Improvement in Annealing-Furnace; and I do hereby declare that the following is a full, clear, and exact description thereof, which will enable those skilled in the art to make and use the same, reference being had to the accompanying drawings, forming part of this specification.

This invention consists in the construction of a furnace for annealing car-wheels, whereby the hubs of the said wheels may be raised to a high temperature without injury to the hardened or chilled rim or tread of the wheel, and also in placing rings of metal between the wheels, as they are placed in the furnace, for the protection of the rims, as will be herein described.

Figure 1 represents a sectional elevation of the furnace, through the line $x x$ of fig. 2.

Figure 2 is a top view with the cover of the furnace taken off.

Similar letters of reference indicate corresponding parts.

A represents the furnace; A' is the furnace-cover; B is the fire-box; B' is the grate; C, the ash-pit; D, the tuyere-iron or pipe, through which a current of air is forced into the furnace through the ash-pit, as seen in the drawing. E represents the car-wheels placed in the furnace for annealing, and resting upon an offset, α , in furnace-wall, as seen in the drawing. F represent rings, which are placed between the wheels for the purpose of protecting the chilled rims or treads of the wheels from the intense heat of the furnace. It is intended that the eyes of the wheels as they are placed together in the furnace shall form a flue, through which the products of combustion shall pass in their course to the outlet-pipe G at the top of the furnace. The upper portion only of the wheels and rings is shown in section, the lower portion of the wheels and rings is shown entire.

The form of the rings will be seen by noticing the section. In diameter they are designed to fill the furnace, and protect the tread of the wheels from the more intense heat which acts upon the hubs.

After subjecting the wheels, when in this position, to the action of the heat for about four hours, (more or less,) the furnace is then closed up, and the wheels are allowed to remain and cool three or four days, or a sufficient length of time; after which time the wheels are ready for use, the strain occasioned by the shrinking of the casting is taken away, and the wheels are consequently stronger and more durable.

I am aware of the patents for annealing cast wheels, granted to A. Whitney and H. W. Moore, and dated respectively April 25, 1848, and December 5, 1865, but as they form no part of my invention, I do not therefore claim them.

What I claim as new, and desire to secure by Letters Patent, is—

The rings F, placed between and supporting the car-wheels, and fitting snugly within the furnace A, whereby the heat is prevented from reaching the chilled tread of the wheel, while the centre is being annealed by intense heat, the whole supported upon the offset α in the furnace, as herein set forth for the purpose specified.

The above specification of my invention signed by me, this 27th day of April, 1867.

W. R. THOMAS.
